[57] **CLAIM**

The ornamental design for a stethoscope cover, as shown and described.

DESCRIPTION

FIG. 1 is a perspective view of a stethoscope cover, showing my new design;

FIG. 2 is a front elevation view;

FIG. 3 is a rear elevation view;

FIG. 4 is a bottom plan view;

FIG. 5 is a top plan view; and,

FIG. 6 is a left side elevation view, the right side elevation view being a mirror image thereof.

The broken line showing of the stethoscope in FIGS. 1 through 6 is for illustrative purposes only and forms no part of the claimed design.
